[57] CLAIM

The ornamental design for a hole punch with ejector for
plastic tubing, as shown and described.

DESCRIPTION

FIG. 1 is a perspective view of the top, left side and
front of a hole punch with ejector for plastic tubing
showing our new design;

FIG. 2 is a bottom plan view thereof;

FIG. 3 is a top plan view thereof;

FIG. 4 is a right side elevational view thereof;

FIG. 5 is a front elevational view thereof, the rear view
being a mirror image.

FIG. 1

FIG. 3

FIG. 4
